UNITED STATES PATENT OFFICE.

WILLIAM H. FELTHOUSEN, OF BALTIMORE, MARYLAND.

CONVEYER.

SPECIFICATION forming part of Letters Patent No. 275,758, dated April 10, 1883.

Application filed March 12, 1883. (No model.)

To all whom it may concern:

Be it known that I, WILLIAM H. FELTHOUSEN, a citizen of the United States, residing at Baltimore, in the State of Maryland, have invented new and useful Improvements 5 in Conveyers, of which the following is a specification.

In the Letters Patent granted to me on the 3d day of October, 1882, No. 265,491, I provide a machine for cleaning and grading peas in which the peas are elevated to a cleaning-screen, and then delivered to the upper one of a series of perforated grading-cylinders. The elevator disclosed in my patent alluded to has 15 not proven generally satisfactory in operation; and it is the object of my present invention to avoid the existing objection and provide novel and efficient means for conveying the peas to the pea-cleaning screen in the patent mentioned without danger of rupturing or breaking the delicate structure of young and fresh peas. This I accomplish by means of a spirally-flanged conveyer-shaft located within a closed cylinder having at one end a hopper 20 and a throat leading from the hopper to the interior of the cylinder, such throat being composed of walls which are arranged diagonally to the axis of the cylinder in such manner that the peas can pass between the curved spaces 25 formed by the spiral flange without danger of the outer edges of the flange shearing the peas in halves or otherwise cutting them between such edges and the lower edge of the wall of the hopper-throat, which extends in the direction 30 the peas are to be moved.

The invention embraces other features, which will be fully hereinafter described and claimed, and illustrated in the accompanying drawings, in which—

40 Figure 1 represents a plan view of a conveyer constructed in accordance with my invention, the hopper itself being omitted; Fig. 2, a longitudinal vertical sectional view on the line xx of Fig. 1, the hopper being in position; Fig. 3, detached views of the parts.

The cylinder is composed of two or more longitudinal semicircular sections, No. 1, each provided at its edge with laterally-projecting perforated ears 2, through which pass pins or 45 bolts 3 for joining the sections together. The longitudinal conveyer-shaft 4 is constructed

with a continuous spiral flange, 5, rectilinear in cross-section, and such flange rests directly upon the lower portion or section of the cylinder, whereby no intermediate supporting-bearings for the shaft itself are required along the length of the cylinder, which is important, in that by this means a continuous unobstructed channel is provided throughout the length of the cylinder, which avoids bringing the peas 60 in contact with any fixture in the cylinder that would break or rupture them. One end of the conveyer-shaft is formed or otherwise constructed with a circular imperforate disk or wheel, 6, which not only serves to close the 65 end of the cylinder, but also provides means for revolving the conveyer-shaft, which may be done by a hand-crank, 7, or through the medium of gearing. The upper portion or section of the cylinder is constructed with a rectilinear opening arranged diagonally with reference to the axis of the same, and from the edges of such opening rise four walls, 8, 8, 9, and 10, the former, 8, 8, constituting the ends of the throat and being parallel to the axis of the 70 cylinder, while the others constitute the sides of the throat and are oblique to the axis of the cylinder. The wall 10 I term the "advance" wall of the throat, for the reason that it stands in the direction in which the peas are moved 75 by the conveyer, and this wall in practice is the only one that need necessarily be arranged obliquely, as the conveyer moving the peas forward would be only liable to shear them in halves by catching them between the outer edge 80 of the conveyer-flange and the lower edge of the hopper-throat. This is avoided by locating the advance wall obliquely, as this construction causes the lower edge of such advance wall to extend in the direction in which the peas are 85 moved, and hence if the peas fall between the flange and advance wall they will be caused to gently and smoothly glide along the lower edge of said wall and fall downward into the lower portion or section of the cylinder, and 90 by the spiral flange be conveyed to the other end of the cylinder and discharged upon the pea-cleaning screen hereinbefore alluded to.

The hopper 11 is of any suitable construction, and is attached to the upper edges of the 100 walls composing the hopper-throat. As here shown, the cylinder-sections are of cast metal,

the upper section being formed integral with the walls composing the hopper-throat; but while such is a desirable construction, I do not wish to be understood as confining my invention thereto.

By the construction of conveyer herein set forth I provide simple, efficient, and reliable means for uniformly lifting the peas and uniformly discharging them upon the cleaning-screen, it being understood that the conveyer-shaft is rotated at slow speed to avoid too rapid thrusting of the peas through the cylinder.

Having thus described my invention, what I claim is—

1. The combination, with a cylinder composed of two longitudinal sections detachably secured together to form a practically closed structure, of a spirally-flanged conveyer-shaft 20 unsupported by bearings intermediate the ends of the cylinder, said cylinder being closed at one end and the upper section constructed with an oblique hopper-throat, substantially as described.

2. The combination, with the cylinder prac-

tically closed along its length, of a spirally-flanged shaft having at one end an attached disk or wheel for closing one end of the cylinder, and a hopper and hopper-throat communicating with the cylinder adjacent to the 30 disk or wheel on the conveyer-shaft, substantially as described.

3. The combination, with the cylinder composed of two longitudinal sections detachably connected, and the upper section constructed with a hopper-throatway the advance wall of which is located obliquely to the axis of the cylinder, of a spirally-flanged conveyer-shaft 35 the planes of which are in contact with the interior surfaces of the cylinder to support the 40 shaft without intermediate supporting bearings thereof, substantially as described.

In testimony whereof I have hereunto set my hand in the presence of two subscribing witnesses,

WM. H. FELTHOUSEN.
